UNITED STATES PATENT OFFICE.

JAMES BAILEY, OF CORNING, NEW YORK, ASSIGNOR TO CORNING GLASS WORKS, OF CORNING, NEW YORK, A CORPORATION OF NEW YORK.

TEMPERATURE-CONTROLLING MEANS.

Application filed June 11, 1923. Serial No. 644,655.

This invention has for its object to provide a novel method of controlling the temperature of heat treating apparatus of the general type shown by United States Letters Patent No. 1,416,595, of May 16, 1922.

By this invention novel means are provided for utilizing the expansion and contraction of a heated cylindrical chamber for the purpose of actuating a valve controlling the heating medium so that when the chamber has been heated to the desired temperature the supply of heat will be reduced, and when the temperature has fallen below that desired the valve will be opened to increase the amount of heat in the chamber.

My invention further consists in the construction, arrangement and combination of the several parts embodied in it as will be hereinafter more fully described and claimed.

In the accompanying drawings wherein I have shown one form of my invention:—

Figure 1, is a side view of a heat treating apparatus of the type disclosed in United States Letters Patent No. 1,416,595, showing the application of my invention thereto, and

Fig. 2, is an end view of the apparatus shown in Fig. 1.

Referring now to the drawings, the apparatus to which my invention is particularly applicable comprises a metallic cylindrical pipe 10, which forms the heating chamber, and is mounted in suitable end bearings 11 in the form of rollers, one end of the pipe having flanges 12 thereon to prevent endwise motion, while the other end of the pipe is provided with an annular flanged plate 13, the purpose of which will be presently described.

Throughout a greater portion of its length the pipe is in a chamber 14, preferably lined with heat insulation 15, and provided with burners 16 by which it may be heated, and by which its temperature at various points throughout its length may be regulated. The pipe carries on one end a sprocket wheel 17 driven by a chain 18 from a motor 19 through a reduction gearing 20, the motor being mounted in the base of the frame.

Gas is supplied to the burners 16 from a supply pipe 21 flexibly connected to a valve 22 mounted on one end of the frame beneath the pipe 10, but slightly offset therefrom as shown by Fig. 2. Shown in the drawings, but forming no part of the present invention are supply pipes 23 which lead from a T connec-

tion 24 in the pipe 21 to other units of the apparatus. An air injector 25 is mounted in the fuel line between the valve 22 and the burners 16 for the purpose of supplying the desired proportion of air to the fuel. By mounting the injector between the valve 22 and the burners when the valve closes thereby reducing the supply of fuel, the amount of air drawn into the fuel line through the injector, will also be automatically reduced, as will be readily understood.

Pivottally mounted as at 29 to the end of the frame, is a vertically disposed arm 26, having its upper end provided with a roller 27 bearing against the face of the plate 13, and its lower end coupled to a stem 28 extending longitudinally from the valve 22.

Assuming that the above described apparatus is in operation, when the heat from the burners 16 heats the chamber 14 the expansion of the pipe 10 will be a true measure of the heat within the chamber. As the pipe expands the plate 13 will move outwardly and at the same time the arm 26 will be swung on its pivot and this action moves the valve stem 28 inwardly thereby reducing the supply of fuel. When the heat in the chamber 14 decreases after the supply of fuel has been reduced, the pipe 10 will contract, and this action permits the parts to return to their normal position.

It is to be understood that the amount of expansion and contraction of the pipe 10 necessary to cause the parts to function as above described is slight and during the operation of the device a slight increase in temperature of the pipe 10 will swing the arm 26 and vice versa, when the temperature of the pipe drops below the required amount for annealing, the movement of the valve will be such as to increase the supply of fuel to the burners.

The several parts of the apparatus herein shown and described may be of any approved design. It is for this reason that I have not gone into a more detailed description of the burners 16, valve 22 and injector 25, because these parts, in varying styles and designs, can be purchased in the open market. However the lower end of the arm 26 should be adjustably connected to the valve stem 28 so that the relative positions of these parts can be altered to suit varying temperatures necessary to obtain proper annealing of different kinds of ware, and this connection should also

be such that if the lower end of the arm 26 is swung inwardly further than necessary to close the valve 22, such movement will not effect a further movement of the valve

5 Modifications may be resorted to without departing from the spirit of the invention herein disclosed.

Having thus described my invention, what I claim is:—

10 In a device for the annealing of glass articles, the combination with a rotating chamber

to receive the articles, of means for heating the chamber, a controller for regulating the heat so imparted, and means for actuating the controller comprising a member having 15 rolling contact with the end of the chamber and adapted to be shifted by the expansion thereof.

In testimony whereof I hereunto sign my name.

JAMES BAILEY.
